A. P. GUSTAFSON

PNEUMATIC ACTION FOR PNEUMATIC MUSICAL INSTRUMENTS

Filed April 19, 1920

Inventor:
Adolph P. Gustafson,

Witness:
A. J. Sauser.

By A. J. M. Reiff Atty.

UNITED STATES PATENT OFFICE.

ADOLPH PETER GUSTAFSON, OF CHICAGO, ILLINOIS, ASSIGNOR TO M. SCHULZ COMPANY, OF CHICAGO, ILLINOIS, A CORPORATION OF ILLINOIS.

PNEUMATIC ACTION FOR PNEUMATIC MUSICAL INSTRUMENTS.

Application filed April 19, 1920. Serial No. 374,849.

To all whom it may concern:

Be it known that I, ADOLPH P. GUSTAFSON, a citizen of the United States, residing at Chicago, in the county of Cook and State 5 of Illinois, have invented a certain new and useful Improvement in Pneumatic Actions for Pneumatic Musical Instruments, of which the following is a full, clear, concise, and exact description, reference being had to the accompanying drawings, forming a part of this specification.

My invention relates to pneumatic actions for pneumatic musical instruments, such as player pianos, piano players, and the like. 15 One of the objects of the invention is to provide a simple, practical and advantageous construction of pneumatic action.

Another object of the invention is to prevent leakage in the action, particularly in 20 connection with the chambers for the valves controlling the power pneumatics of the action.

In the accompanying drawings Fig. 1 is 25 a cross section of a pneumatic action embodying my present invention;

Fig. 2 is a similar cross section taken at one side of the section of Fig. 1;

Fig. 3 is a plan view of the action.

Referring to the drawings I show a wind 30 trunk 1 forming part of a pneumatic action which is understood to be suitable for use in a player piano in connection with the piano action. This wind trunk 1 preferably comprises upper and lower members 1^a and 1^b, respectively, which may be made of wood or other suitable material. These two members 1^a and 1^b are secured together, as 35 by screws 2—2, arranged in rows along the edges of said members as shown in Fig. 3.

The upper member 1^a is provided with a longitudinally extending groove or channel 3 and the lower member 1^b with a longitudinally extending groove or channel 4, these two channels 3 and 4 together forming 40 a windway 5 which is understood to be in communication with suitable wind inducing apparatus, such as a pneumatic bellows, so as to produce in windway 5 a pressure either greater or less than atmospheric 45 pressure, preferably a reduced pressure or partial vacuum.

Below the wind trunk 1 pneumatics 6—6 are arranged crosswise of the wind trunk 1, as shown in Fig. 3. Each of these pneumatics 55 5 is intended to operate a piano

action, the loose leaf 7 of the pneumatic for that purpose being preferably provided with a lug or projection 8 adapted to engage a projection on the sticker of the piano action.

The valve mechanisms for controlling pneumatics 6—6 comprise small pneumatics 9—9 arranged at intervals along the wind chamber 5. Each of these pneumatics 9 has a lower member 10 which rests on the 60 bottom of the wind trunk member 1^b and is secured thereto, and a swinging member 11 hinged to the member 10, and having a bleed port nipple 11^a, said member 11 also carrying a valve stem 12 having a hooked 65 end 13 carrying a valve 14. The valve 14 is arranged in a valve chamber 15 and rests on a valve seat 16. A cap or closure 17, in the form of a circular pasteboard disk, closes the top of the valve chamber 15, said 70 cap 17 however, having an aperture 18 forming a port controlled by valve 14, and also forming an aperture through which the valve stem 12 may pass to permit 75 engagement of the hook 13 with said valve 14. The port or opening 18 controls communication between the windway 5 and valve chamber 15. A duct or passage 19 extends downwardly from valve chamber 15, the upper end of said duct or passage 19 80 forming a port also controlled by valve 14. The duct or passage 19 leads to a channel 20 extending along the under side of the wind trunk 1, and communicating with the outside air. A duct or passage 21 extends 85 between valve chamber 15 and interior of pneumatic 6, whereby the latter may be put in communication with wind chamber 5 or outside air, according as valve 14 is in lower or upper position. Valve 14 is controlled by 90 pneumatic 9, which is in turn controlled by a tracker board tube 22 and passage 23 in member 1^b.

As a matter of further improvement the 95 annular edge of the cap or closure 17, or at least a substantial part of that annular edge, is covered by the portion 24 of the upper member 1^a of the wind trunk 1, as best shown in Figs. 2 and 3. In this way a 100 very advantageous construction is made. The closures 17 are held in position by the portions or shoulders 24, as well as by the glue usually applied to the under sides of members 17, the latter being thus in effect 105 held between two substantial and rigid walls 110

or abutments, so that changes in pneumatic pressure even though quick and violent, cannot dislocate said members 17. Furthermore, leakage around the annular edges of members 17 is prevented, thus effectively stopping leakage at points or areas where it might occur and considering the large number of members 17 in an action, contributing materially toward producing an absolutely tight action.

It will be understood that changes and modifications may be made without departing from the spirit of the invention.

What I claim is:

- 15 1. In a pneumatic action the combination of a closure for a valve chamber, said closure being provided with an aperture forming a port controlled by the valve member, and means substantially completely covering the edge portion of said closure.
- 20 2. In a pneumatic action the combination of a wind trunk composed of upper and lower members, the lower member having valve chambers, closures for said valve chambers, said closures being provided with apertures forming valve ports, valves in said chambers and means for actuating said

valves, the upper member of said wind trunk having portions overlying and substantially completely covering the edge portions of said closures.

3. In a pneumatic action the combination of a wind trunk composed of upper and lower members secured together, the lower member being provided with valve chambers, disc-like members forming closures for said valve chambers and having apertures forming valve ports, valves in said chambers, pneumatic means for controlling said valves, said pneumatic means being located in the windway of the wind trunk and being connected with the valves through said apertures in said disc-like members, and pneumatics secured to the under side of said wind trunk, the upper member of said wind trunk having annular portions covering the joints of said closures with the under wind trunk member and also substantially entirely covering edge portions of said closures.

In witness whereof, I hereunto subscribe my name this 8th day of April, A. D. 1920.

ADOLPH PETER GUSTAFSON.
